CHARLES SHIRLEY, OF BROOKLYN, NEW YORK, AND JOHN F. SKIRROW,
OF EAST ORANGE, NEW JERSEY.

TELEGRAPH-KEY.

SPECIFICATION forming part of Letters Patent No. 685,301, dated October 29, 1901.

Application filed August 6, 1901. Serial No. 71,055. (No model.)

To all whom it may concern:

Be it known that we, CHARLES SHIRLEY, a subject of the King of Great Britain, residing in the borough of Brooklyn, county of Kings, 5 city and State of New York, and JOHN F. SKIRROW, a citizen of the United States, and a resident of East Orange, county of Essex, State of New Jersey, have invented certain new and useful Improvements in Telegraph- 10 Keys, of which the following is a specification, reference being had therein to the accompanying drawings, in which—

Figure 1 is a perspective view of the key; Fig. 2, a vertical sectional view of the same; 15 Fig. 3, a side elevation, and Fig. 4 a front elevation, of a slightly-different form of the key from that shown in Fig. 1.

This invention relates to new and useful improvements in telegraph-keys; and it has 20 for one of its objects to provide a key which is rotatable upon its support to adapt it to be operated by the right hand or by the left hand with equal facility and to enable the operator to place it in any desired position.

25 Another object of the invention is to so construct the key that it may be operated by holding the operating-handle in the palm of the hand or by pressing on the handle with the palm or any other part of the hand or with 30 the wrist or by grasping the handle in the fingers and the signal sent with an arm movement instead of grasping it with the fingers and making the signals entirely by wrist motion, as is necessary in the proper use of an 35 ordinary signaling-key.

Referring to the various parts by numerals, 1 designates a hollow vertical case or support, which is formed at its lower end with the rearward-extending foot 2, through which the 40 thumb-screw 3 passes to rotatably secure the case to the table. The case at its top is formed with the two bearings 4 and 5, which are separated a short distance from each other and are arranged one at the front and one at 45 the back of the case. Projecting forward from the front bearing is a horizontal sleeve 6, in which is mounted a rock-shaft or movable bar 7, which is journaled in the bearings 4 and 5. On this shaft and filling the 50 space between the two bearings 4 and 5 is a collar 8, which is held against rotation by

means of set-screws 9, threaded through the collar and bearing on the shaft. Secured to this collar is a depending contact-carrying arm 10, which extends into the case 1 a considerable distance and is provided at its lower end with a downward-extending lateral finger 11, to which one end of a coil-spring 16^a is secured. The other end of this spring is secured to the upper end of one arm of an angle-lever 12, which is pivoted on a horizontal pin 13. This pin is rigidly secured to the front of the case and extends rearward through the removable back 14, its outer rear end being threaded to receive the nut 15, 55 which secures the removable back in place. Threaded through the left-hand side of the case is a tension-adjusting screw 16, whose inner end bears on the other arm of the angle-lever 12 and by means of which the tension 60 of the spring 16^a on the contact-carrying bar may be increased or diminished, as desired. Secured on the left-hand side of the contact-carrying bar is a slight flat spring 17, whose lower end tends to spring away from the bar 65 10, its movement away from the bar being limited by the adjusting-screw 18. On this spring, near the lower end thereof, is mounted a contact-point or circuit-terminal 19, and threaded through a bushing of insulation 80 fitted in the left-hand side of the case is a screw 20, whose inner end forms the other contact or circuit-terminal, against which the contact 19 strikes during the operation of 70 transmitting signals. 85

It will be noted that by loosening the screws 9 the shaft may be rotated independently of the collar 8, so that, if desired, the operating-handle may be fixed to the shaft and the shaft rotated to put the handle in the desired 90 position, and the collar is secured in position by the screws 9. It will thus be seen that the arm and the shaft are rotatably adjustable with respect to each other.

Within the casing, on the right-hand side 95 thereof, directly opposite and in line with the contact-screw 20, is a stop 30, against which the lower end of the contact-carrying bar is drawn by the tension-spring 16^a. Within the casing, at the lower end thereof, is secured a 100 block 31, of insulating material, which carries a spring contact-plate 32, to which is con-

5 nected one wire of the circuit, the other wire of the circuit being connected to the case 1 by means of a screw 31^a, which passes through the block of insulating material and into the case. The contact-plate is connected by an insulating-wire 32^b to the contact-screw 20, and a cut-out lever 33 is pivoted on the horizontal pin 13, its lower end being adapted to engage the contact-plate 32, and thereby put 10 said plate in electrical connection with the case 1 to cut out of circuit the contact-screw 20. The upper end of this lever is provided with a thumb-piece 34, which projects through a slot in the front of the case in convenient 15 position for manipulation. An opening is made in the front of the case to enable the operator to see that the contact-points are properly adjusted and are in good working condition.

20 On the forward end of the rock-shaft 7 is the operating-handle 25. This handle may be secured to the shaft in any suitable manner; but it is preferred to secure it thereto by means which will permit of its adjustment 25 to any radial position around said shaft. As shown in Fig. 1, the handle is connected, by means of a ball-and-socket joint, to a short bar 26, which is pivoted at its rear end to the forward end of the rock-shaft, and clamping- 30 screws 27 are provided at the inner end of the handle and at the forward end of the rock-shaft, whereby the handle may be placed in any desired position and then securely clamped therein. It will be seen that by 35 means of the bar 26 the handle may be raised or lowered and that by means of the ball-and-socket joint between the handle and the bar 27 the handle may be adjusted to any radial position around the shaft, and in addition it may be placed at any desired angle 40 with respect to the rock-shaft. Instead of securing the handle to the rock-shaft by means of a ball-and-socket joint the shaft may be threaded at its outer end and provided with 45 a collar near the outer end of the sleeve 6, and the handle may be provided with a sleeve 28, which fits over the outer end of the shaft, its inner end bearing against the collar on the shaft and being clamped thereon by means 50 of a thumb-nut 29, which is threaded on the outer end of the rock-shaft. By this means the operating-handle is adjustable to any position around the shaft, but is always perpendicular thereto.

55 The handle is secured to the rock-shaft by means of friction grips or clamps in both of the forms of devices described. The object of this is that the position of the handle may be changed without unscrewing or otherwise 60 loosening the fastening means, it being simply necessary to exert a sufficient pressure on the handle to move it in the desired direction and to the desired position. This is very advantageous, as when the operator once places 65 the clamping means at the proper tension to hold the key to the shaft when sending signals it will not be necessary to alter that ten-

sion or to operate the clamping means when it is desired to change the position of the handle. It also enables the operator to shift the position of the handle instantly whenever it is desired. It is of course obvious that the pressure on the handle during the act of sending signals is very light and that therefore the grip of the clamping means will not be necessarily very great. 75

As shown in Fig. 1, the key is operated by grasping the handle in the right hand and swinging it downward slightly, thereby rocking the shaft 7 and causing the contact carried by the arm 10 to strike the end of the contact-screw 20. It will be noted that the handle is universally adjustable about the rock-shaft in order that the operator may place it in any desired position and may readily change its position in order that certain muscles may be rested while others are brought into play. It will also be noted that the adjustable contact and the tension-adjusting screw are on the left side of the case 85 in proper position to be readily manipulated by the left hand without interfering with the sending of signals by the right hand.

To adapt the instrument to the use of left-handed operators, it is rotatably mounted on the table or support by means of the screw 3 and may be swung half-way around to bring the adjusting-screws 20 and 16 in position to be manipulated by the right hand and the operating-handle in position to be grasped by the left hand. In this position the handle is also swung downward slightly in sending signals, as will be readily understood from Fig. 2, in which view the key is shown in position to be used by a left-handed operator. In this position, however, the casing is between the handle and the operator and the handle is in a position not quite so convenient or capable of such a variety of adjustments as when it is in front of the casing, as it is in Fig. 1. In order, therefore, that the key may be adapted for both right and left handed operators and the handle be in front of the case in both forms, a rearward-extending horizontal sleeve 35 is formed on the rear bearing 4 of the case, 90 said sleeve being axially in line with the sleeve 6, and the rock-shaft is extended through both sleeves. On the projecting ends of the shaft are rigidly secured collars 36, the extreme ends of the shaft being threaded for 95 the reception of the clamp-nut 29. In this form the handle is provided with the sleeve 28 at its inner end, which sleeve is arranged at right angles thereto and is adapted to slide over the ends of the shaft and bear at its inner end against one of the collars 36 and be clamped in place and held against rotation on the shaft by the thumb-nut 29. When it is desired to reverse the key, the thumb-nut and handle are removed from the forward 100 end of the rock-shaft, the casing given a half-rotation to bring the other end of the shaft forward, and the handle and nut then placed on this forward end of the shaft. 105

The advantages of a key that may be reversed and readily adapted for use with either the right or the left hand are very great and will be readily appreciated by telegraph-operators. It is well known that in using the ordinary signaling-key the wrist-muscles soon become very tired and frequently inflamed and often paralyzed by the constant strain on them. Many operators have a number of keys on their tables set in various positions, some placed for the use of the right hand and others for the left in order that they may change positions and use either hand. It is necessary, however, in order to send clear signals with an ordinary key that the button on the end thereof be firmly grasped by the thumb and first two fingers and that the motion be entirely a wrist motion. It will be seen that when an operator is working steadily from eight to ten hours a day there is a tremendous strain on these muscles of the wrists, and all manner of expedients are resorted to to relieve them. In the present invention the key is operated by an arm movement, the operating-handle being grasped in the hand and swung bodily in the direction necessary to bring the contacts together, and the handle being universally adjustable around the shaft and the entire instrument being reversible it will be readily seen that the key may be so used that a great variety of muscles will be brought into action. If desired, the operator can place the handle in such a position that he may operate the key in the ordinary manner, using the thumb and fingers to grasp the handle and moving it with a wrist motion. By placing the handle in a horizontal position and rotating the support until the end of the handle points toward the operator and is in position to be grasped by the thumb and fingers it will be readily seen that the key can be operated in practically the same manner as is the ordinary key.

It will be readily understood that a handle may be secured on each end of the shaft in the form of device shown in Fig. 4, so that it will be simply necessary to reverse the position of the instrument in order to convert it from a right-hand key to a left-hand key, or vice versa.

Any suitable rotatable support may be employed instead of the case shown, and the rock-shaft or movable bar may be vertical or inclined, if found desirable.

Having thus fully described our invention, what we claim, and desire to secure by Letters Patent, is—

1. In a telegraph-key the combination, of a support, a rock-shaft mounted thereon, an arm mounted on the rock-shaft and adapted to make and break the circuit, an outward-extending handle carried by the rock-shaft, the handle and the arm being adjustable with respect to each other around the rock-shaft, and a tension device to move the arm and the handle in one direction.

2. In a telegraph-key the combination, of an inclosing case, a horizontal rock-shaft mounted in said case, an arm on said rock-shaft and extending outward therefrom, its outer end being within the case and adapted to make and break the circuit, an operating-handle adjustably secured to the rock-shaft outside of the case, and a tension device to move the arm and the handle in one direction. 70

3. In a telegraph-key, the combination of a support, a rock-shaft mounted thereon, an outward-extending arm having one terminal of a circuit connected thereto, means for securing said arm to the rock-shaft to permit the shaft and the arm to be rotatably adjusted with respect to each other, means for supporting the other terminal of the circuit in position to be engaged by the terminal on the 85 arm and an operating-handle carried by the rock-shaft.

4. In a telegraph-key, the combination of a rotatable support, a horizontal rock-shaft mounted in the upper end of said support, an 90 arm carried by said rock-shaft and carrying one terminal of a circuit, means for supporting the other terminal in position to be engaged by the terminal carried by the arm of the rock-shaft, and an operating-handle secured to one end of the rock-shaft.

5. In a telegraph-key, the combination of a support, means for rotatably mounting said support, a movable bar carried by the support and having one terminal of a circuit connected thereto, means for supporting the other terminal of the circuit adjacent the terminal carried by the movable bar and in position to be engaged thereby, an operating-handle and frictional gripping means for securing the handle to the movable bar whereby the handle may be shifted without loosening the gripping means. 100

6. In a telegraph-key, the combination of a support, a rock-shaft mounted thereon and carrying one terminal of a circuit, means for supporting the other terminal in position to be engaged by the terminal carried by the rock-shaft, an operating-handle, and frictional gripping means for securing the handle to the rock-shaft whereby it may be adjusted to various positions around said shaft without loosening the securing means and radially extend therefrom. 115

7. In a telegraph-key, the combination of a 120 support, a rock-shaft mounted thereon and carrying one terminal of a circuit, means for supporting the other terminal in position to be engaged by the terminal carried by the rock-shaft, an operating-handle, and frictional gripping means for connecting the handle to the rock-shaft whereby it is universally adjustable about said shaft.

8. In a telegraph-key, the combination of a 130 rotatable support, a rock-shaft carried thereby and having secured to it one terminal of a circuit, means for supporting the other terminal of the circuit in position to be engaged by the terminal carried by the rock-shaft, an

- operating-handle, and means for securing it to the rock-shaft, whereby said handle may be adjusted to various positions around said shaft and extend radially therefrom.
9. In a telegraph-key, the combination of a rotatable support, a rock-shaft carried thereby and having one terminal of a circuit connected thereto, means for supporting the other terminal of the circuit in position to be engaged by the terminal carried by the rock-shaft, an operating-handle and means for securing it to the rock-shaft whereby it is universally adjustable about the rock-shaft.
10. In a telegraph-key, the combination of a support, a rock-shaft mounted thereon, an arm carried by said shaft and having secured thereto one terminal of a circuit, a tension-spring connected to said arm, means for adjusting said spring, means for adjustably supporting the other terminal of the circuit in position to be engaged by the terminal on the arm, the tension-adjusting and terminal-adjusting means being on the same side of the support, and an operating-handle connected to the rock-shaft and adapted to extend toward the opposite side of the support whereby the adjusting devices may be manipulated by one hand while signals are being sent by the other hand.
11. In a telegraph-key, the combination of a hollow case, a horizontal rock-shaft mounted in the upper end of said case, a depending arm on said rock-shaft extending into the case and carrying a contact-point which forms one terminal of a circuit, an adjustable terminal carried by the case in position to be engaged by the contact on the arm, a tension device connected to the depending arm, an operating-handle connected to the rock-shaft.
12. In a telegraph-key, the combination of an upright hollow case, a horizontal rock-shaft mounted in the upper end of said case, a depending arm on said rock-shaft extending into the case and carrying a contact-point which forms one terminal of a circuit, a tension device connected to the arm on the rock-shaft, means for adjusting the tension of this device, an adjustable terminal carried by the case in position to be engaged by the contact on the depending arm, the tension-adjusting means and the adjustable terminal being on the same side of the case, and an operating-handle adapted to be connected to one end of the rock-shaft, and adapted to extend radially therefrom away from the adjusting devices.
13. The combination of a hollow case, a horizontal rock-shaft mounted thereon, a depending arm on said shaft and extending within the case and carrying a contact, a tension device connected to said arm, a contact-point carried by the case and insulated therefrom and in a position to be engaged by the contact on the arm, a contact-plate carried by the case and insulated therefrom and connected to one wire of a circuit the other wire of the circuit being connected to the case, an insulated wire connecting said contact-plate to the contact-point carried by the case, a cut-out lever pivoted on the case and adapted to engage the contact-plate, and an operating-lever connected to the rock-shaft.
14. In a telegraph-key, the combination of a rotatable support, a rock-shaft mounted thereon and extending therethrough and adapted to receive an operating-handle on either end, an arm on said shaft carrying one terminal of a circuit, means for supporting the other terminal of the circuit, and an operating-handle adapted to be secured to either end of the rock-shaft by frictional gripping means.
15. In a telegraph-key, the combination of a rotatable support, a rock-shaft carried thereby, an arm carried by said shaft and having secured thereto one terminal of a circuit, said rock-shaft being adapted to receive an operating-handle on either end, means for supporting the other terminal of the circuit in position to be engaged by the terminal carried by the arm, and an operating-handle adapted to be secured to either end of the rock-shaft, and to be adjusted to various radial positions around said shaft.
16. In a telegraph-key, the combination of a rotatable hollow case, a horizontal rock-shaft mounted therein, a depending arm secured to said rock-shaft within the case and carrying one terminal of a circuit, means for supporting the other terminal in position to be engaged by the terminal carried by the arm on the rock-shaft, and an operating-handle adjustably secured to one end of the rock-shaft outside of the case.
